FURNACE WITH TUBE SUPPORTED ROOF

Howard J. Kerr, Westfield, N. J., assignor to The Babcock & Wilcox Company, Bayonne, N. J., a corporation of New Jersey

Application June 12, 1930, Serial No. 460,727

13 Claims. (Cl. 110—99)

This invention relates to a furnace that may be provided with wall cooling tubes and has cooling tubes extending across the top or roof of the furnace, upon which roof tubes are supported or suspended in such a manner that injured tile can be readily removed and replaced with others.

The invention will be understood from the description in connection with the accompanying drawings in which Fig. 1 is a longitudinal vertical section through an illustrative embodiment of the invention; Fig. 2 is a similar view partly broken away, taken at right angles to Fig. 1; Fig. 3 is a view similar to Fig. 2, showing a modification; Figs. 4, 6, 8, 10, 12, 14 and 16 are sectional views on enlarged scales, showing modifications of tile and connections to the tubes; and Figs. 5, 7, 9, 11, 13, 15 and 17 are sections along the corresponding section lines of Figs. 4, 6, 8, 10, 12, 14 and 16.

In the drawings, reference character 1 indicates a furnace that may be fired by means of one or more fuel burners 2 extending through the roof of the furnace. Horizontally disposed headers 3 are located along the side walls of the furnace and are connected by cooling tubes 4 in the side walls of the furnace to upper horizontally disposed headers 5, which are preferably located at about the level of the roof of the furnace.

In the illustrative embodiment of the invention, the lower portion 6 of the furnace is suitable for containing glass that may be melted. The glass may be introduced through the inlet 7 and the molten glass passes out through the outlet 8.

Water may be passed into the headers and through the tubes to cool the walls of the furnace, the heat being used to generate steam that may be used for any desired purpose. Horizontally disposed roof tubes 10 extend between the headers 5. One or more intermediate points of the tubes 10 may be connected by means of pivoted connections 11 to a support 12, thereby supporting the intermediate portions of the tubes. The headers 5 are supported in any convenient way and serve to support the ends of the tubes 10.

In the modification shown in Fig. 3, the tubes 10 are divided into two sections, the inner ends of the tubes being bent upwardly, as indicated at 13, to enter the longitudinal header 14 that may be supported in any convenient manner, thus supporting the tubes.

Tile 15 are suspended from or supported by the tubes 10, the lower ends of the tile being large enough to cover substantially the entire surface 55 of the roof on the furnace side. Each tile 15 is

provided with a reduced portion or neck 16 with an enlarged head 17 at the top, the heads 17 providing lateral projections at the upper ends of the tile.

Rectangularly shaped blocks 18 with one corner cut out to provide a curved surface 19 to fit against the tubes 10 are interposed between the tubes 10 and the lateral projections at the upper ends of the tile 15. As shown in Figs. 4 to 7, for example, two rows of blocks 18 are provided for each tube 10, these rows of blocks fitting into the recesses 20 of the tile 15 along side of the reduced portions or necks 16. Other rectangular blocks 21 are interposed between the blocks 18 and the lateral projections on the heads 17.

The tile 15 are installed by passing the reduced portions upwardly between the rows of tubes 10 until the curved corners 15' of the tile contact with the tubes 10. The blocks 18 are then passed through the spaces between the heads 17 and put in place on the tubes 10. The blocks 21 are then put in place and the tile 15 let down into the position shown in Figs. 4 or 6. The tile can be readily removed by raising them slightly and then removing the blocks 18 and 21, after which the tile can be taken out in a downward direction.

The modification shown in Figs. 6 and 7 differs from that shown in Fig. 4 in that the recesses 20 are made longer and blocks 22, having semi-circular surfaces 22', are located below the tubes 10.

In the modification shown in Figs. 8 and 9 wedge-shaped blocks 23 with one side curved and the other straight, having a semi-circular recess 24 in the straight side for contacting with the tubes 10, are placed against the tubes 10 with the blocks 21 between their upper surfaces and the extending projections on the heads 17. The recesses 20' in the tile 15 are shaped to correspond to the blocks 23, leaving enough space between the lower ends of the blocks 23 and the shoulders on the tile 15 to permit the tile to be raised slightly for removing the blocks 21 and 23.

In the modification shown in Figs. 10 and 11, wedge-shaped blocks 25 with curved surfaces 26 and wedge-shaped blocks 27 with curved surfaces 28 extend into the recesses 29 along the necks of the tile 15 and keep the tile in place. These blocks can be removed by slightly raising the tile 15 and first removing the blocks 25 and then the blocks 27.

In the modification shown in Figs. 12 and 13 wedge-shaped blocks 30 and arcuate-shaped blocks 30' and 30'' are used to keep the tile 15 in

place. The tile practically surround the tubes 10 and approximately semi-circular recesses 31 are provided in the tile into which recesses the blocks extend.

5 In the modification shown in Figs. 14 and 15 blocks 32 and 32' are used to keep the tile in place. These tile have curved surfaces to fit the tubes 10 and extend into the recesses 33 in tile 15. The ends of the blocks 32' rest against the 10 sides of the blocks 32.

In the modification shown in Figs. 16 and 17, blocks 34 in the shape of semi-circular segments in cross section extend into corresponding recesses 35 to keep the tile 15 in place.

15 In the modification shown in Figs. 14 to 17 an extra row of cooling tubes 10' is provided along the upper ends of the tile 15 and similar rows of cooling tubes may be provided in the other modifications.

20 It will be understood that while this invention has been described in connection with a glass furnace, it is not restricted to this use but can be applied equally well to any other furnace roof structure.

25 I claim:

1. In a furnace, elongated supports spaced from each other along the roof of said furnace, tile supported by said supports, said tile having reduced portions extending between said supports, 30 and pairs of blocks at different elevations between said supports and tile.

2. In a furnace, elongated supports spaced from each other along the roof of said furnace, tile supported by said supports, said tile having reduced portions extending between said supports, 35 and removable blocks between each support and tile, one of which removable blocks contacts with a support and another one with a tile.

3. In a furnace, elongated supports spaced from each other along the roof of said furnace, tile supported by said supports, said tile having reduced portions extending between said supports, laterally extending portions above said reduced portions, and pairs of blocks at different elevations between said supports and laterally extending portions. 40

4. In a furnace, elongated supports spaced from each other along the roof of said furnace, tile supported by said supports, said tile having reduced portions extending between said supports, 45 and laterally extending portions, said blocks having a dimension less than the distance between said laterally extending portions and also less than the distance between said supports and said laterally extending portions.

5. In a furnace, elongated supports spaced from each other along the roof of said furnace, tile supported by said supports, said tile having reduced portions extending between said supports, and pairs of blocks of different sizes between said supports and tile. 50

6. In a furnace, elongated supports spaced from each other along the roof of said furnace, tile supported by said supports, said tile having reduced portions extending between said supports, and pairs of blocks of different sizes between said sup-

ports and tile at least one block of each pair having a curved surface to contact with a support.

7. In a furnace, cooling tubes along the roof of said furnace, contacting tile supported by said tubes, said tile having lateral projections above said tubes, and pairs of blocks at different elevations between said projections and tubes. 5

8. In a furnace, cooling tubes along the roof of said furnace, contacting tile supported by said tubes, said tile having lateral projections above 10 said tubes, and pairs of blocks between said tubes and tile one block of each pair contacting with a tube and the other with a tile.

9. In a furnace, cooling tubes along the roof of said furnace, contacting tile supported by said 15 tubes, said tile having lateral projections above said tubes, and pairs of blocks between said tubes and tile, one block of each pair being smaller than the other one.

10. In a furnace, cooling tubes along the roof 20 of said furnace, contacting tile supported by said tubes, said tile having lateral projections above said tubes, and blocks between said projections and tubes, said blocks having a dimension less than the distance between edges of the projections on adjacent tile and also less than the distance between said tubes and said projections. 25

11. In a furnace, elongated supports spaced from each other along the roof of said furnace, tile supported by said supports, said tile having 30 reduced portions extending between said supports, and pairs of blocks between said supports and tile, the blocks of each pair contacting with each other.

12. In a furnace, a plurality of tubes spaced 35 in a lateral plane, tile adapted to be inserted upwardly between said tubes, said tile being recessed on sides that are adjacent, thus providing cooperating recesses to span an area substantially surrounding the lower half of each tube when the 40 tile are assembled in position, each tile having receiving recesses for tile sustaining means in the respective faces of the portions thereof that extend upwardly between the tubes, said last-named recesses being above said first-named recesses and 45 adjacent the respective tubes, and tile sustaining means encompassing substantially the upper half of each tube and engaging said receiving recesses of adjacent tile to removably maintain the tile in position. 50

13. In a furnace, a plurality of elongated supports spaced in a lateral plane, tile adapted to be inserted upwardly into position between said supports, said tile being recessed on sides that are adjacent, thus providing spaces to span substantially the lower half of each support when the tile are assembled in position, each tile having a receiving recess for tile sustaining means in the respective faces of the portions thereof that extend upwardly between the supports, said last-named recesses being above said first-named recesses and adjacent the respective supports, and tile sustaining means surrounding substantially the upper half of each support substantially closing the space above said support and engaging 60 said receiving recesses of adjacent tile to maintain the tile removably in position. 65

HOWARD J. KERR.
